CLAIM

The ornamental design for a pet harness, as shown and described.

DESCRIPTION

FIG. 1 is a top, front, left perspective view of a pet harness showing my new design in a condition of use;

FIG. 2 is a top, front, left perspective view of the pet harness of FIG. 1;

FIG. 3 is a top, rear, right perspective view thereof;

FIG. 4 is a front elevational view thereof;

FIG. 5 is a rear elevational view thereof;

FIG. 6 is a right-side elevational view thereof;

FIG. 7 is a left-side elevational view thereof;

FIG. 8 is a top plan view thereof; and,

FIG. 9 is a bottom plan view thereof.

In the drawings, the longer, equal-length broken lines on the pet harness depict unclaimed portions thereof, and form no part of the claimed design. The shorter equal-length broken lines on the pet harness depict stitching and form no part of the claimed design. In FIG. 1, the broken lines that show a dog depict environmental matter and form no part of the claimed design. The dash-dot-dash broken lines define the bounds of the claim. All of the broken lines form no part of the claimed design.
